Attorney

UNITED STATES PATENT OFFICE.

JOHN O'BRIAN, OF THORN HILL, CANADA.

ADJUSTABLE SIEVE.

SPECIFICATION forming part of Letters Patent No. 469,488, dated February 23, 1892.

Application filed June 4, 1891. Serial No. 395,109. (No model.)

To all whom it may concern:

Be it known that I, JOHN O'BRIAN, a subject of the Queen of Great Britain, residing at Thorn Hill, Manitoba, Dominion of Canada, 5 have invented certain new and useful Improvements in Adjustable Sieves; and I do declare the following to be a full, clear, and exact description of the invention, such as will enable others skilled in the art to which it applies to make and use the same.

My invention has relation to improvements in sieves such as employed in thrashing-machines; and it has for its object to provide a construction of sieve-embodying devices 15 adapted to be adjustably fixed, whereby the size of the meshes or openings for the passage of the grain may be increased or diminished, so as to adapt the sieve for employment in connection with various kinds of 20 grain, &c.

To the attainment of the foregoing object the invention consists in the construction, novel combination, and adaptation of parts hereinafter described and claimed.

25 In the accompanying drawings, Figure 1 is an inverted plan view of my improved sieve; and Fig. 2 is a section of the same, taken in the plane indicated by the line $x-x$ on Fig. 1.

Referring by letter to the said drawings, A 30 indicates the main frame of my improved sieve, which is preferably of a rectangular contour, and may be made of any material suitable to the purpose sought to be attained. Preferably stepped or recessed at its 35 ends and connected to the upper side of the end bars of the frame A at about the middle thereof is a bar B, which is designed and adapted to form one of the bearings for one end of each transverse slat, as will be 40 presently described. Extending vertically through the bar B at about the middle thereof is a bolt C, which has its lower end threaded to receive a nut D, which serves, in conjunction with other devices, to adjustably fix 45 the adjustable bar, as will be presently described. The adjustable bar E is provided at or adjacent to its middle with a vertically-

disposed longitudinal slot a, through which the bolt C passes. Extending through the adjustable bar E from the lower side thereof 50 are set-screws F, which bear at their upper ends against the under side of the fixed bar B and serve to fix the distance between the fixed and adjustable bars, while the nut D of bolt C retains the adjustable bar in such position. 55

G indicates the transverse slats of the sieve, which are preferably of the proportional thickness and width illustrated, and are of a length corresponding to the distance between 60 the bars B and E and the side bars of the rectangular frame A. These slats G are respectively provided at their outer ends adjacent to their upper edge with a lug which takes into the inner side of the side bars of 65 the frame A, which form a bearing for the outer ends of the slats, and at their inner ends said slats are provided with lugs adjacent to their upper and lower edges, which lugs are journaled, respectively, in the fixed bar B and 70 the adjustable bar E whereby it will be perceived that when said bar E is adjusted the inclination of the several slats will be varied and the openings between the same increased and diminished, as is obvious. In some instances I contemplate dispensing with the 75 fixed bridge-bar B, in which case the bolt C would take through one of the side bars of the frame upon which the adjustable bar E would be mounted, and the slats would extend entirely across the frame instead of half-way, as illustrated.

Having described my invention, what I claim, and desire to secure by Letters Patent, is—

85 As an improved article of manufacture, the thrashing-sieve described, comprising the rectangular frame, the central longitudinal bridge-bar secured at its opposite ends to the cross-bars of the frame, the adjustable bar 90 E, having the longitudinal elongated slot a therein, the bolt secured to the bridge-bar and passing through the slot in the adjustable bar, a nut on said bolt for holding said

bar E in its adjustable relation to the bridge-bar, the set-screws passing through the adjustable bar and adapted to bear against the bridge-bar, so as to separate the same, and
5 the slats pivotally connected at opposite ends near one longitudinal edge to the main frame and bridge-bar, respectively, and pivotally connected at their inner end near the oppo-

site longitudinal edge to the slotted adjustable bar, substantially as specified.

In testimony whereof I affix my signature in presence of two witnesses.

JOHN O'BRIAN.
